UNITED STATES PATENT OFFICE.

FREDERICK C. HOWARD, OF SPOKANE, WASHINGTON.

DESIGN FOR A KEY-TAG.

44,406.

Specification for Design.

Patented July 29, 1913.

Application filed May 12, 1913. Serial No. 767,218. Term of patent 14 years.

To all whom it may concern:

Be it known that I, FREDERICK C. HOWARD, a citizen of the United States, residing at Spokane, in the county of Spokane and State of Washington, have invented a new, original, and ornamental Design for Key-Tags, of which the following is a specification, reference being had to the accompanying drawing, forming part thereof.

The figure is a side elevation of a key tag, showing my new design.

I claim:

The ornamental design for a key tag, as shown.

FREDERICK C. HOWARD.

Witnesses:

J. E. McANDREW,
FRED C. DOHLIN.
